(57) **CLAIM**

I claim the ornamental design for a ladder top, as shown and described.

DESCRIPTION

FIG. 1 is a front perspective view of the ladder top showing my design.

FIG. 2 is a top plan view thereof;

FIG. 3 is a bottom view thereof;

FIG. 4 is an end view;

FIG. 5 is the opposite end view, which is identical the view in FIG. 4;

FIG. 6 is a front view thereof;

FIG. 7 is a back thereof; and,

FIG. 8 is a perspective view thereof, showing attachment to a ladder in broken lines.

The broken lines are presented for illustrative purposes only and form no part of the claimed design.
